No. 37,387.

Patented April 4, 1905.

UNITED STATES PATENT OFFICE.

EDWARD TAYLOR, OF ROCKFORD, ILLINOIS, ASSIGNOR TO ROCKFORD SILVER PLATE COMPANY, OF ROCKFORD, ILLINOIS, A CORPORATION OF ILLINOIS.

DESIGN FOR A SPOON.

SPECIFICATION forming part of Design No. 37,387, dated April 4, 1905.

Application filed March 8, 1905. Serial No. 249,125. Term of patent 7 years.

To all whom it may concern:

Be it known that I, EDWARD TAYLOR, a citizen of the United States, residing at Rockford, in the county of Winnebago and State of Illinois, have invented a certain new and original 5 and ornamental Design for a Spoon, of which the following is a specification, reference being had to the accompanying drawings, forming part thereof.

Figure 1 is a front face view of a spoon, show-

ing my design. Fig. 2 is a rear face view of the spoon.

What I claim as new, and desire to secure by Letters Patent, is—

The ornamental design for a spoon, as shown. 15

EDWARD TAYLOR.
